WALTHER BAUERSFELD, OF JENA, GERMANY, ASSIGNOR TO THE FIRM OF CARL ZEISS, OF JENA, GERMANY.

TELEMETER.

1,347,571.

Specification of Letters Patent. Patented July 27, 1920.

Application filed October 6, 1914. Serial No. 865,406.

To all whom it may concern:

Be it known that I, WALTHER BAUERSFELD, a citizen of the German Empire, residing at Jena, Germany, have invented a new and 5 useful Telemeter, of which the following is a specification.

The present invention relates to telemeters having the base-line in the instrument, in which the members of the requisite reflecting 10 system can be brought into two locations, in which they have different relative positions, the difference between the said two positions being such that two different base-lines result, the said two positions being such, however, that, on passing from one position to the other, the relative location of the two images of an infinitely distant object presented to the observer does not change independently of the relative position of those 15 members of the reflecting system, which are fixed together. Of this type of telemeter only one single kind has up to the present become known, viz. the one dealt with in the Patent Specification 1,085,883. In this kind 20 of telemeter a reflecting system belonging to the front part of the telemeter can be brought into two different locations; in both locations its error of reflexion is the same, both as regards its absolute value and its 25 sign, consequently the telemeter as a whole has the property alluded to, that the relative location of the two images presented to the observer is not altered by an interchange of the two positions, which the members of 30 the entire reflecting system (viz. the movable reflecting system on the one hand and the fixed reflectors on the other hand) can occupy relatively to one another. The two base-lines belonging to a telemeter of this 35 kind are the base-line proper, which is used when taking a range, and a second one, which is used when the instrument is being adjusted and with which the two entering axial rays have the distance zero from one 40 another in the plane of triangulation, i. e. a base-line, which also has the value zero. As is known from the Patent Specification 1,085,883, it is possible to adjust such a telemeter with the aid of an object at any desired distance without additional auxiliary 45 means.

The telemeter according to the present invention differs from the telemeters just mentioned by having both its base-lines different from zero. While the new telemeter

is just as simply adjustable as the telemeters according to Patent 1,085,883, it can be fitted with such simple reflecting systems as are only possible with the other telemeters, when forms are employed, which are hardly 60 suitable for being carried out in practice.

With the telemeters having the base-line within the instrument the measurement rests, as is well known, on the principle, that the range is proportional to the product derived 65 from the length of the base-line and the reciprocal of the value of the angle formed at the object, the range of which is to be found, by the rays coming from the said object to the ends of the base-line. Hence, 70 when the telemeter has been adjusted, a single reading will suffice, for finding the size of the said angle and by that means the required range. When there are doubts as to the state of adjustment of the telemeter, 75 with the telemeters not corresponding to Patent 1,085,883 an auxiliary measurement is carried out for an object having a known distance (e. g. an infinitely great one), with the telemeters according to Patent 1,085,883, 80 for an object of unknown distance, the instrument, however, being temporarily given a base-line having the value zero.

In the new telemeter an object having an unknown distance is used, just as in the 85 case of the telemeter according to Patent 1,085,883, for adjusting, however, a double measurement of the following kind is made with the two base-lines belonging to the telemeter. In the first place an auxiliary 90 measurement is made for an object having any distance, this measurement being based on one of the base-lines, and with the aid of the adjusting device of the telemeter the indication infinity is obtained, whereupon 95 another measurement is made for the same object with the other base-line. By this double measurement the angle has obviously been determined, which at the object, the range of which is to be found, the two 100 rays form with one another, which are directed toward the ends of a base-line equal to the difference of the two base-lines of the telemeter. From this angle the distance of the object employed may be derived in any 105 suitable manner, the value of the base-line being based on the difference between the two base-lines used. Should it be desired to avoid specially deriving the range from the angle, a scale may be employed when 110

measuring the angle, which, like the usual scales of telemeters, indicates ranges directly. When that scale of the telemeter is used, which is intended for the measurements proper, its readings apply equally to the double measurements serving for the adjustment, if these readings be multiplied by the quotient from the difference between the two base-lines belonging to the telemeter and the length of the base-line on which the scale is based. In principle nothing would stand in the way of fitting the telemeter with a single range-scale only, which is based on the difference between the two base-lines, and employing the method of adjustment described, which after all gives the true range of the object employed. For the purpose of reducing the time taken over the single measurements, however, it will be found generally of advantage to carry out such an adjustment measurement with the aid of both base-lines only from time to time, as a rule, however, to use only one of the two base-lines for measuring. The true range of any suitable object may then be from time to time ascertained by a double measurement of the kind described and the scale intended for the measurements proper correspondingly corrected.

This method of adjustment corresponds to that described briefly in the British Patent 5,267 of the year 1901 (p. 4, l. 23 to l. 35). The telemeter, however, for which the adoption of this method is there recommended, differs substantially from the present one. The telemeter there described consists of a prism field-glass provided with a measuring device and in front of which there is placed a reflecting system, the object of which is to increase the relative distance of the entrance axes of the telemeter with regard to that of the entrance axes of the field-glass. The second base-line (in the above meaning of the term) results, when the field-glass is used by itself. Hence, the unavoidable variations in the deflection of the rays, effected by the said reflecting system, do not make their influence felt with both measurements to be undertaken for the adjustment of the telemeter, while it is just the condition for an adjustment, which is independent of such variations, that the variations of the kind described act on both measurements, and in the same sense too.

As the adjustment of the new telemeter is based, as explained above, on the difference between the two base-lines, its accuracy increases, the greater the said difference. A difference, the absolute value of which is greater than one of the two base-lines themselves, will obviously result, when one of the base-lines is given a value, the sign of which is opposite to that of the other base-line. This may be taken as re-

alized, when the ray pencil entering the instrument in the one case to the right of the observer enters in the other case to his left hand and vice versa.

The greatest absolute value of the said difference, assuming the greatest base-line length, is obtained, when the two base-lines are opposite to one another as regards their signs and agree as to their absolute value.

While in the case, in which the two base-lines agree as regards their absolute size, it is immaterial, which of the two is taken as the basis of the measurements proper, the greater one should be utilized for the said measurements, when the two base-lines differ from one another in their absolute value.

As the double measurement serving for the adjustment is based on the difference between the two base-lines, its accuracy, when the two base-lines have different signs, is greater than that of the measurements proper. Hence, it may be even recommended in certain cases to carry out a double measurement of the kind described in place of one of the measurements proper, for instance on any occasion when it happens to be desirable to obtain an increased accuracy of measurement.

In the annexed drawing Figure 1 is a diagrammatic plane view of the optical system of a telemeter according to the invention. Figs. 2 and 3 show another such system in its measuring disposition and in its auxiliary measuring disposition serving for adjustment respectively. Figs. 4 to 7 show a third system, Figs. 4 and 6 being plan views and Figs. 5 and 7 cross-sections on lines 5—5 and 7—7 of Figs. 4 and 6 respectively. Figs. 4 and 5 represent one disposition and Figs. 6 and 7 the other disposition. Figs. 8 to 11 show a fourth system, Figs. 8 and 10 being front elevations, while Figs. 9 and 11 are plan views. Figs. 8 and 9 represent one disposition and Figs. 10 and 11 the other disposition.

In the optical system of Fig. 1 in front of either of two objectives *a* is a pentagonal prism *b*. A separating prism system of a well-known kind, consisting of two prisms *c*¹ and *c*², which are cemented together, transmits the ray pencils coming from the ends of the base-line to an ocular *d*¹, *d*². Behind the left-hand objective there is a glass wedge *e*¹, which is displaceable in the direction of the axial ray passing through it and which represents the adjusting device of the telemeter. A similarly displaceable glass wedge *e*² behind the right-hand objective indicates the measuring device. When the measurements proper are being made, the pentagonal prisms are in the position shown in full lines. Should it be desired for adjusting the telemeter to carry out the double measurement described

- above, first of all the pentagonal prisms are shifted into the position shown in dotted lines and the first measurement is made with this position (to which a reduced base-line corresponds). Thereupon the pentagonal prisms are again brought into the position indicated in full lines and with this position the second measurement is made.
- 10 In Figs. 2 and 3 the optical parts are the same as in the example according to Fig. 1. For the auxiliary measurement, however, the right-hand objective prism, b^2 , in this case remains in its position, while the left-hand one, b^1 , is removed from the left-hand end of the instrument and is placed after being rotated through 180° in the plane of its principal section, before the right-hand end. While in the former measuring position the direction of the base-line is, as usual, perpendicular to the direction of inspection into the instrument, in the latter position it is parallel to the same; hence, the whole instrument must be rotated, when 25 changing from one position to the other, through 90° .
- In the next example, Figs. 4 to 7, the two base-lines are opposed to one another as regards their sign in the above explained 30 sense, while they agree as to their absolute size. The optical parts are again the same as in the example according to Fig. 1, the entrance axis of the left-hand pentagonal prism, b^1 , being, however, oppositely directed to that of the right-hand pentagonal prism, b^2 . In order to give both sides of the telemeter the same direction of outlook, in the position according to Figs. 4 and 5 a central reflector b^0 is disposed in front of the right-hand pentagonal prism. In the position according to Figs. 6 and 7 the same central reflector is placed in front of the other pentagonal prism. While in the position according to Figs. 4 and 5 the direction of inspection of the instrument agrees with its direction of outlook, they are oppositely directed in the position according to Figs. 6 and 7. Hence, when using this system, the former position will generally be 45 used for the measurements proper and the latter position for the auxiliary measurement. On passing from one position to the other, the whole instrument must be rotated in the plane of triangulation through 180° .
- 50 In the last example, Figs. 8 to 11, the sign of the base-line in the first position is opposite to that of the base-line in the second position, in their absolute size, however, the base-lines of the two positions agree.
- 60 With the position as in Figs. 8 and 9 a pentagonal prism again lies in front of each objective, both, however, with their surface of emergence turned away from the adjacent objective, the left-hand prism, b^1 , being displaced downward and the right-hand one, b^2 , upward with respect to the objectives. The separating prism system c^1 , c^2 , the ocular d^1 , d^2 and the wedges e^1 and e^2 again correspond to the same parts of the former examples. Two central reflectors f^1 and f^2 serve for transmitting the rays emerging from the left-hand pentagonal prism to the left-hand objective and those emerging from the right-hand pentagonal prism to the right-hand objective. The 70 position according to Figs. 10 and 11 is obtained from this position by both pentagonal prisms being rotated in the plane of their principal section through 90° , the left-hand one, b^1 , in the clockwise and the right-hand one, b^2 , in the opposite direction; in addition to this the left-hand prism is displaced upward and the right-hand one downward beyond the objectives. The rays emerging from the left-hand pentagonal prism, b^1 , now enter at the right-hand end of the telemeter the central reflector f^2 and are transmitted by it to the right-hand objective; the rays emerging from the right-hand pentagonal prism, b^2 , enter at the 80 left-hand end of the telemeter the central reflector f^1 and are transmitted by it to the left-hand objective.
- The adjustment of a telemeter according to the invention shall be explained with the aid of the last example. In the position according to Figs. 10 and 11 by displacing the measuring wedge e^2 the indication infinity is set on a range-scale and for any object coincidence of the two measuring images is obtained by displacing the adjusting wedge e^1 . Thereupon, by rotating and displacing the objective prisms the system is brought into the condition according to Figs. 8 and 9 and by the displacement of 90 the measuring wedge e^2 the coincidence of the measuring images, which was lost by the rearrangement of the parts, is reestablished for the same object. The reading on the said scale now gives the true distance 100 of said object. By displacing the measuring wedge this reading is established on a second range-scale, the graduations of which have half the relative distance of those of the first scale and the thus lost coincidence 105 of the measuring images reestablished by displacing the adjusting wedge. The telemeter is now adjusted.
- I claim:
1. In a telemeter containing two base-lines differing from zero an objective system, a reflecting system, the members of which are adapted to be brought into two different relative positions, each base-line belonging to one such position of the said 120 members, the relative location of the two images of an infinitely distant object presented to the observer by the telemeter remaining unaltered, on passing from the use of one base-line to the use of the other base- 125
- 65 130

line, independently of the relative position of those members of the reflecting system, which are fixed together, and range-indicating means.

5. 2. In a telemeter containing two base-lines differing from zero an objective system, a reflecting system, the members of which are adapted to be brought into two different relative positions, each base-line 10 belonging to one such position of the said members, the relative location of the two images of an infinitely distant object presented to the observer by the telemeter remaining unaltered, on passing from the use 15 of one base-line to the use of the other base-line, independently of the relative position of those members of the reflecting system, which are fixed together, and range-indicating means comprising two scales, one 20 such scale being based on one of the said base-lines, while the other scale is based on the difference between the two base-lines.
3. In a telemeter containing two base-lines differing from zero and having opposite signs, an objective system, a reflecting system, the members of which are adapted to be brought into two different relative positions, each base-line belonging to one such 25 position of the said members, the relative location of the two images of an infinitely distant object presented to the observer by the telemeter remaining unaltered, on passing from the use of one base-line to the use 30

of the other base-line, independently of the relative position of those members of the reflecting system, which are fixed together, and range-indicating means. 35

4. In a telemeter containing two base-lines differing from zero and agreeing as to their absolute value, two objectives, an objective reflecting system located at either end of the telemeter and consisting of an optical square and of a central reflector, each optical square, when used in connection with one of the base-lines, being adapted to 40 transmit, together with the central reflector lying at the same end of the telemeter, and, when used in connection with the other base-line, being adapted to transmit, together with the central reflector lying at the other end of the telemeter, the rays entering the optical square to that objective, which lies at the same end as the central reflector, the relative location of the two images of an infinitely distant object presented to the observer by the telemeter remaining unaltered, on passing from the use of one base-line to the use of the other base-line, independently of any variation of the angle of deflection of either optical square or of either central 45 reflector, and range-indicating means. 50
